[57] CLAIM

The ornamental design for a deck construction game, as shown and described.

DESCRIPTION

FIG. 1 is a perspective of the deck construction game, showing the square deck component of the kit design; FIG. 2 is a top plan view thereof;

FIG. 3 is a front elevational view thereof;

FIG. 4 is a rear elevational view thereof;

FIG. 5 is a right side elevational view of both the square and the rectangular components of my kit design, the left side elevational views being, respectively, mirror images thereof;

FIG. 6 is a perspective view of the rectangular deck component of my kit design;

FIG. 7 is a top plan view thereof;

FIG. 8 is a front elevational view thereof; and,

FIG. 9 is a rear elevational view thereof.

The undisclosed bottoms of the components of my kit design are plain and unornamented.

FIG. 1

FIG. 2

FIG. 3

FIG. 4

FIG. 5

FIG. 6

FIG. 7

FIG. 8

FIG. 9
